UNITED STATES PATENT OFFICE.

CHARLES W. BECK, OF DETROIT, MICHIGAN, ASSIGNOR TO THE BECK-FROST CORPORATION, OF DETROIT, MICHIGAN, A CORPORATION OF MICHIGAN

STEERING WHEEL.

Application filed April 21, 1924. Serial No. 708,656.

To all whom it may concern:

Be it known that I, CHARLES W. BECK, a citizen of the United States of America, residing at Detroit, in the county of Wayne 5 and State of Michigan, have invented certain new and useful Improvements in Steering Wheels, of which the following is a specification, reference being had therein to the accompanying drawings.

10 This invention relates to steering wheels and consists of certain novel features of construction and combination of parts as hereinafter set forth.

In the accompanying drawing:

15 Figure 1 is a top plan view of a steering wheel embodying my invention;

Figure 2 is a sectional view taken on line 2—2 of Figure 1;

20 Figure 3 is a sectional view taken on line 3—3 of Figure 1;

Figure 4 is a plan view of a portion of my steering wheel when inverted before the flanges are secured to the projections of the shell;

25 Figure 5 is a sectional view taken on line 5—5 of Figure 2.

Referring now to the drawing in which like characters of reference designate corresponding parts throughout the several 30 views, the numeral 1 designates a rim preferably of wood, detachably secured to a spider 2 which includes a hub 3 and a plurality of radially extending arms 4.

The hub preferably comprises a sheet 35 metal shell 5 that is provided at its upper end with flared radially extending projections 6 having depending flanges 7 at the opposite side edges thereof. Located within the shell 5 is a metallic core 8 which is 40 preferably a die casting and is provided with a tapering bore 9 for receiving a suitable steering stem (not shown). The core 8 is also preferably provided at its upper end with radially extending projections 12

45 having longitudinally extending recesses 13 therein that receive the spider arms 4. These arms are preferably formed of wood and are preferably cut away at their inner ends as shown at 8' to provide a shoulder 50 9' for engagement with the outer ends of the projection 6. Suitable headed elements such as screws 14 are preferably driven through openings 15 in the projections 12 and into the arms 4 to hold the latter in the 55 recesses 13.

For concealing the core 10 and holding the same in the shell 5, I preferably provide a top plate 16 that conforms in shape to the upper surface of the core and is provided with marginal flanges 17 that extend downwardly between the arms 4 and are preferably crimped over the flanges 7 of the shell 5. Thus, the plate 16 and flanges 7 co-operate with the shell 5 to form a housing for the core. In this connection it will be noted that the flared portions 19 of the top plate project slightly beyond the projections 12 of the core to a point in vertical alignment with the ends of the projections 6 and engage transversely extending notches 20 in the upper surface of the arms 4.

In the process of construction, the arms 4 are first inserted in the recesses 13 and are then secured to the projections 12 by means of the screws 14. The assembled 75 arms and core are then placed upon the inverted top plate 16 as shown in Figure 4 of the drawing, whereupon the shell 5 is slipped upon the core so that the projections 6 abut the arms. In order that the shell 5, core 10 and cover plate will be secured together in a single operation, the flanges 17 are then crimped over the depending flanges 7 as shown in Figures 2 and 5 of the drawing to provide the finished steering wheel.

From the foregoing description it will be readily apparent that I have provided an exceptionally strong and durable steering wheel of the built-up type that can be manufactured at a comparatively low cost. This is especially so in view of the fact the time required for building up the wheels is reduced to a minimum by securing the core, shell and top plate together in a single 90 operation. It will also be apparent that the depending flanges 17 of the top plate engage the curved side edges of the projections 12 and thereby prevent the core 10 from moving or turning relative to the shell 5. Furthermore, the arms 4 will be held securely in position in the recess 13 by the screws 14 which pass through the holes 15 in the projections 12 and also by the portions 19 of the top plate which engage the notches 20 in the upper surfaces of the arms 4.

While it is believed that from the foregoing description the nature and advantages of the invention will be readily apparent, I desire to have it understood that I do not 110

limit myself to what is herein shown and described, and that such changes may be resorted to when desired as fall within the scope of what is claimed.

6. What I claim as my invention is:

1. In a steering wheel, the combination with a rim and a plurality of arms secured thereto, of a hub including a shell, a core within the shell and having portions secured 10 to the arms, and a cover plate upon the core secured to the shell.

2. In a steering wheel, the combination with a rim and a plurality of arms secured thereto, of a hub including a shell having 15 projections supporting the arm, a core within the shell having portions extending upon opposite sides of the arms, and a cover plate upon said core having flanges secured to said projections.

20 3. In a steering wheel, a hub including a shell, and a core within the shell, a plurality of spider arms connected to one of said elements, and a cover plate engaging one of said elements and secured to the other of 25 said elements.

4. A steering wheel spider comprising a hub having a shell and a core within the shell, a plurality of arms secured to said core, and a cover plate concealing the core 30 and secured to the shell.

5. In a steering wheel, a hub including a shell and a core within the shell, a plurality of projections upon the shell, a plurality of arms resting upon the projections, 35 means for securing the arms to the core, and a cover plate upon the core having flanges secured to the projections of said shell.

6. In a steering wheel, a hub including a shell having radially extending projections, a core within the shell having projections disposed above the projections of the shell, a plurality of radially extending arms disposed between the projections of the core and shell, and means for securing 40 45 the arms to the projections of said core.

7. In a steering wheel, a hub including a shell having radially extending projections, said projections having longitudinally extending embossed portions, a core within the shell having radially extending projections 50 extending above the projections of the shell, the last-mentioned projections having longitudinally extending recesses therein, a plurality of radially extending arms engaging the embossed portions of the first-mentioned projections and disposed in the recesses in the last-mentioned projections, and means for holding said arms in the recesses and in engagement with the embossed portions aforesaid.

8. In a steering wheel, a hub including a shell having radially extending projections, a plurality of radially extending arms resting upon the said projections, a core within the shell having projections secured 55 to the arms, and a top plate upon said core having flanges extending downwardly between the arms and return-bent against the projections of the shell.

9. In a steering wheel, a hub having a 60 shell and a core in said shell, a series of projections extending radially from said core, a series of spider arms secured to said projections, and a cover plate for said core secured to said shell.

10. In a steering wheel, a hub having a shell and a core in said shell, projections extending radially from said core, arms secured to said projections, projections upon 65 said shell engaging said arms, flanges carried by the last-mentioned projections, and a cover plate upon said core having flanges crimped over the flanges aforesaid.

11. In a steering wheel, a hub including a shell, a core in the shell having radially 70 extending recesses, and arms engaging said recesses and secured to said core.

In testimony whereof I affix my signature.

CHARLES W. BECK.
